United States Patent Office.

SAMUEL LOCKARD, OF LAGRANGE, INDIANA.

Letters Patent No. 82,331, dated September 22, 1868.

IMPROVEMENT IN PISTON-ROD PACKING.

The Schedule referred to in these Letters Patent and making part of the same.

TO ALL WHOM IT MAY CONCERN:

Be it known that I, SAMUEL LOCKARD, of Lagrange, in the county of Lagrange, and State of Indiana, have invented a new and useful Improvement in Piston-Rod Packing; and I do hereby declare that the following is a full, clear, and exact description thereof, which will enable those skilled in the art to make and use the same, reference being had to the accompanying drawings, forming part of this specification.

This invention relates to an improvement in packing around the piston-rods of steam-engines, and which method is adapted to other purposes; and it consists in the arrangement of conical packing-rings in a chamber provided for the purpose in the cylinder-head, and surrounding the said split packing-rings with a follower, and with a spiral spring, as will be hereinafter described.

The drawing—

Figure 1, represents a vertical section of the arrangement.

Figure 2 is an end view of the packing-rings and the follower.

Figure 3 is a vertical section of fig. 2 through the line *z z*.

Similar letters of reference indicate corresponding parts.

A is the cylinder-head.

B is the piston-rod.

C is the cap, which screws on to the collar of the cylinder-head.

d is a spiral spring.

e is the inner packing-ring, and *f* is the outer packing-ring. The inner one fits the piston-rod, as does the lower portion of the outer one. These rings are cut, so that they can be compressed.

g is the follower, which fits on to the outer ring, as seen in the section, fig. 3, with a collar, *h*, around its top.

The spiral spring *d* bears against the collar *h*, and surrounds the follower and rings, as seen in fig. 1.

This packing-arrangement is placed in a chamber, *K*, formed in the cylinder-head, and covered by the cap, *C*.

L represents orifices in the bottom of the chamber *K*, for admitting steam from the cylinder.

The spring, which rests on the bottom of the chamber *K*, bears against the collar of the follower, and holds it in close contact with the outer packing-ring, which is crowded up against the under side of the cap, which insures a tight joint at that point.

When steam is admitted into the chamber *K*, the packing-rings are more or less compressed around the piston-rod, and crowded upward by the steam-pressure, so that the joint around the piston-rod must always be steam-tight, but I do not depend entirely upon the pressure of the steam for this purpose.

Ordinarily, the elasticity of the packing-rings and the pressure of the spiral spring will be found sufficient to produce a steam-tight joint around the piston-rod, and through the head.

It will be seen that the top of the collar *h* does not reach to the top of the packing-rings, so that in pressing upwards, the spring *d* compresses the packing around the piston-rod; consequently, if the steam-orifices *L* were closed, the joint would not leak steam under ordinary circumstances.

I do not, therefore, confine myself exclusively to either device, but propose to use the packing either with or without the steam-pressure, as may be deemed most advisable.

Having thus described my invention, I claim as new, and desire to secure by Letters Patent—

The arrangement, within the chamber *K*, of the conical split packing-rings *e f*, flanged follower *g*, and spring *d*, as herein shown and described.

SAMUEL LOCKARD.
